UNITED STATES PATENT OFFICE.

OSCAR LIEBREICH, OF BERLIN, GERMANY.

PROCESS OF MANUFACTURING SOAP.

SPECIFICATION forming part of Letters Patent No. 308,968, dated December 9, 1884.

Application filed October 7, 1884. (No specimens.) Patented in Germany April 12, 1884, No. 29,290; in England April 17, 1884, No. 6,472; in Belgium April 26, 1884, No. 64,945, and in France April 26, 1884, No. 161,756.

To all whom it may concern:

Be it known that I, OSCAR LIEBREICH, a subject of the King of Prussia and Emperor of Germany, and a resident of the city of Berlin, 5 in the Kingdom of Prussia and German Empire, have invented certain Improvements in the Process for the Manufacture of Soap, (for which I have obtained a patent in Germany, No. 29,290, dated April 12, 1884; a British patent, No. 6,472, dated April 17, 1884; a patent in Belgium, No. 64,945, dated April 26, 1884, and a French patent, No. 161,756, dated also April 26, 1884,) of which the following is a specification.

15 My invention relates to an improvement in the process for the manufacture of soap—namely, hard soap—consisting, substantially, in the use of centrifugal force for the separation from the lye.

20 In the process now generally employed for the production of hard soap this is separated from the lye after the salting process by drawing off the lye. The nucleus or hard soap thus obtained is then either cut out after cooling, 25 or it is boiled down and run into molds. The product thus obtained is rendered more or less impure by the lye and salt remaining therein, the lye having, on account of its alkaline constituents, a detrimental effect upon the fabrics 30 treated therewith, as also on the colors thereof, while the salt diminishes the cleansing properties and consequently the value of the soap.

The present invention has for its object the production of a hard soap that shall be practically almost completely freed from the lyes, 35 and that shall contain much less salt than ordinary curd, while at the same time a much harder and more neutral product is obtained, containing also less water (from twenty to 40 twenty-five per cent.) than that obtained in the ordinary way.

In carrying out the improved process the soap, separated by salt by the known methods, and before its separation from the lye by complete cooling has taken place, is introduced into a centrifugal machine driven at a high speed, 45 and is subjected while in a heated condition to centrifugal action for a comparatively short time (from four to at most twenty minutes.)

The centrifugal apparatus can be of any suitable known construction that permits of the specifically heavier lye flowing off at the proper place, while the soap is condensed by the centrifugal action either against the sides of the drum itself or in special molds or buckets, 55 if a bucket centrifugal machine be employed. After being subjected to this centrifugal action the soap is practically entirely freed from the lyes and contains only a small quantity of the salt, and a much smaller percentage of water than is ordinarily the case, while the specific density is greatly increased, the product 60 being perfectly neutral.

The soap may, if necessary, be subject to a further cooling, which, however, would be of 65 but short duration, either in the centrifugal machine itself, under the application of cold water, if necessary, or the molds or buckets or even the centrifugal drum itself can be removed for this purpose and be placed in a cool- 70 ing-chamber.

If the salting has been effected under a dilute condition of the lye, it might in some cases be of advantage to allow the soap to settle from the lye for a short time before the centrifugal action is applied, in order to have to 75 remove a somewhat less quantity of liquid by such action.

The application of centrifugal action in the hot condition as described is also effective in 80 those cases where according to the ordinary methods a complete separation of the soap is not possible or very difficult—as is the case, for instance, with the saponification of cocoanut-oil. With this the separation of the soap 85 by the existing methods is so difficult, (some soap-makers even assert that cocoanut-oil cannot be converted into hard soap at all,) and the separated product is so porous when effected at all, and so saturated with salt solution, 90 that it is generally preferred to treat cocoanut-oil together with other oils of which the soap is more easily separated. With the centrifugal action, however, even the separation of cocoanut-oil soap can be perfectly effected, resulting 95 in a hard neutral product free from lye and containing a low percentage of water.

As further advantages of the described pro-

cess may be mentioned, first, that the greater or less degree of concentration at which the salting is effected is without influence upon the product obtained, a product of uniform quality being obtainable by due regulation of the duration of the centrifugal action; second, that in the cases which sometimes occur where the soap has a tendency to remain in the granular condition the centrifugal action nevertheless 5 converts it into a solid compact mass, thereby dispensing with repeated solution of the soap, which is otherwise necessary; third, that the entire separation requires much less time, so that for a large production a considerable saving in cost is thus effected, in addition to the 10 advantage of obtaining a better, harder, and 15

perfectly neutral product free from lye and containing less percentage of salt and of water.

Having now described my invention and also the process for performing it, what I claim is— 20

In the manufacture of hard soap, subjecting the said soap immediately after the salting and before the cooling to centrifugal action, substantially in the manner and for the purpose herein set forth. 25

In testimony whereof I have signed my name to this specification in the presence of two subscribing witnesses.

OSCAR LIEBREICH.
